UNITED STATES PATENT OFFICE

CHARLES A. BUCHANAN, OF PLAIN CITY, OHIO, ASSIGNOR, BY MESNE ASSIGNMENTS, TO THE GRISWOLD MANUFACTURING COMPANY, OF ERIE, PENNSYLVANIA, A CORPORATION OF PENNSYLVANIA

HAIR WAVER

Application filed December 5, 1930. Serial No. 500,311.

My invention relates to improvements in hair wavers and the object of the invention is to secure a hair waver of simple and economical construction which shall be effective in 5 operation and is adapted to be operated by the person whose hair is to be waved or by an outside operator.

The invention consists in the novel construction and arrangement of parts herein-after more fully described and set forth in the claims.

In the accompanying drawings which illustrate this invention:

Fig. 1 is a top plan view showing the general arrangement of parts.

Fig. 2 is a side elevation partly broken away.

Fig. 3 is a bottom plan of the same.

Fig. 4 is a transverse section of Fig. 3.

Fig. 5 is a perspective of a removable shield.

Figs. 6 and 7 are diagrammatic views showing the position of the teeth in the operation of producing the hair waves and the movement of the hair from normal to waved position.

The device consists primarily of two parts 1 and 2 hinged together in scissors-like formation. Each of these parts 1 and 2 is of fork construction each having two prongs 3 and 4 and 5 and 6. One of the parts such as 1 is preferably slotted as shown at 7 and the other part 2 extends through this slotted opening and the parts being pivoted together at their juncture as shown at 8. The backwardly extending portions from the pivot are each provided with handles 9 and 10 by means of which the parts 1 and 2 may be brought together or separated to closed or open positions in scissors-like fashion.

The main part 1 along the under side of the respective prongs 3 and 4 has projecting comb-like teeth 11 and the corresponding prongs 5 and 6 of the other part 2 are slotted as at 12 and 13 so that when the parts are brought together in closed position the slotted openings of the part 2 are brought over the teeth 11 in part 1.

There is mounted between the prongs 3 and 4 of part 1 a sliding member 14. This sliding member is also provided with comb-like

teeth 15 similar to those in the adjacent prongs 3 and 4. These teeth 15 are in two rows preferably staggered with reference to each other and the teeth in each row are preferably less in number than the corresponding teeth in the prongs 3 and 4 so that the teeth in the sliding member when in normal position are in staggered relation to the teeth in the respective prongs.

Means are provided for reciprocating the sliding member between the prongs of the main member 1 which consists preferably of a toggle-jointed or lazy-tongs construction composed of the pivoted levers 16 and 17 pivoted together at 18 and provided at the rear extensions with upturned parts 19 and 20 adapted to be engaged by the fingers of the operator. These respective levers 16 and 17 are connected from their outer extremities to the sliding member by links 21 and 22 which are pivoted to the outer extremities of the levers at one end and at the other by a pivot 23 with the sliding member. Springs 24 connecting the pivoted levers 16 and 17 on opposite sides of their pivot 18 serve to hold the sliding member in its normal or closed position. By pressing on the finger portions 19 and 20 the sliding member may be moved longitudinally in relation to the prongs of the main member 1 and cause the teeth in the sliding member to move with relation to the teeth of the main member against the tension of the springs 24 and when released the parts will be returned to their normal position. The device in its simplest form may be operated as follows: The main parts 1 and 2 are separated by means of the handles 9 and 10 and the plain slotted prongs of the parts 2 are slipped under the hair next to the scalp of the person whose hair is to be waved. The parts are then closed so that the hair is clamped more or less between the upper portion 1 and the lower portion 2. The sliding member is then operated by pressing the inwardly projecting ends of the toggle-jointed lever together which forces the sliding member longitudinally and outwardly between the tooth members and thus moves a portion of the hair between the points where it is held and this causes a wavy-like appearance.

In order to produce a more or less permanent set in the hair that is operated upon the sliding member is provided with a heating unit preferably electrically operated. This 5 heating unit is so formed and proportioned that it may be connected to any ordinary electric wiring system and the heating element will be brought to the proper temperature to secure the necessary more or less permanent 10 wave in the hair.

When the heating unit is used the parts which may come in contact with the scalp of the person whose hair is being waved may become heated and would therefore be unpleasant 15 in contact with the scalp. To obviate this I provide a shield 25 preferably of heat insulating material such as bakelite or similar substance which is adapted to slip over the prong which will be at the point where 20 the waving is to start. This shield is of U-shape and is adapted to slip longitudinally over the prong at one side of the groove so as not to interfere with the groove passing over the teeth and it is also provided at one 25 end with an inturned part which will extend over the end of the prong in a cup-like manner and at the inner extremity with a spring clasp to fit the prong and hold the shield in position. (See Fig. 5.) This protects the 30 scalp from the heat of the prong in case the temperature shall be raised, and inasmuch as the other prong need not rest against the scalp the shield on one prong only is necessary.

This shield also performs another function. It is of a sufficient thickness on its top portion so that when the parts are closed together in scissors-like formation to clasp the hair the upper portion of this shield will clamp tightly against the lower portion of 40 the corresponding prong in the part 1 and thus clasp the hair tightly on this side at the same time forming a clearance between the other prong and its corresponding part in the upper portion which will permit the hair to 45 move more or less freely through these parts. By this arrangement when the device is first put into operation the prong of the part 2 next to the point at which the waving operation begins is covered with the shield. The 50 hair is clasped tightly therefore at this point with the teeth on the respective prongs and on the movable slides engaging the hair at different points. The current being turned on the heating element is brought to the 55 proper temperature and the movable slide is moved longitudinally pushing that portion of the hair between the two prongs of the part 1 into a wave-like formation, that portion of the hair between the shield 25 and the corresponding prong is held tightly and prevents 60 pulling of the hair on the scalp while the hair may be drawn more or less freely through the teeth of the other side sufficiently to form the wave. The device is left in position a sufficient 65 length of time to secure a more or less

permanent set. The parts are then separated by means of the handles and removed and the operation repeated at a point adjacent to where the first wave stopped. The clasping of the hair at the point of starting by means of the shield 25 in the continued operation prevents the hair from being drawn from the waves already formed and thus distorting the same. This operation is continued until all 70 that part of the wave on one side of the middle portion of the hair is completed. The shield is then shifted to the other prong and that portion of the hair on the opposite side of the middle portion or part is waved in a similar manner, the hair being held clasped at the point of starting and adjacent to each 75 finished wave while it is free to be drawn in between the teeth to form the succeeding waves, without disturbing or distorting the waves already formed or pulling of the hair 80 at the scalp in the starting operation. The hair necessary to form the wave being drawn from the free ends or that portion of the hair which has not been waved.

It has been found in practice that by having the teeth staggered in the sliding member and also staggered in relation to the teeth in the more or less stationary part or prongs of the part 1 that the waves are formed in a more perfect wave-like manner and of attractive 85 appearance than if the teeth were aligned.

Having thus described my invention, I claim:

1. A hair waver which consists essentially of two parts hinged together in scissors-like formation, each of the parts being forked with extending prongs, each of the prongs in one of the parts having comb-like teeth and the prongs in the other part adapted to lie respectively adjacent at least the inner sides 100 of said teeth when the prongs are in closed position, a sliding element located between the toothed prongs of one member, handles on the pivoted portion for opening and closing the same and means in proximity to these 105 handles for causing a sliding movement of the sliding member.

2. A device such as described in claim 1 characterized by having teeth in the prongs and sliding member respectively that are in 110 staggered relation to each other.

3. A construction such as described in claim 1 in which multiple rows of teeth are embodied in the sliding member, the teeth in one row being staggered with relation to the 115 other.

4. A construction such as claimed in claim 1 in which the teeth in the sliding member are in staggered relation to the teeth in the pronged member and also in staggered relation to each other.

5. A hair waver consisting of two principal members hinged together in scissors-like formation, each being of forked construction with extending prongs, the prongs in one part 120

having projecting teeth and the prongs in the other part having openings to fit over said teeth and a detachable shield adapted to be attached to one of the prongs of that member 5 having the openings, said shield being of insulating material.

6. In a hair waver formed of two principal parts hinged together in scissors-like formation, one of said parts being provided with 10 projecting teeth arranged in parallel relation on opposite sides thereof and a sliding member between these parts also having projecting teeth in parallel relation to the teeth in the main member, a heating unit forming 15 a part of said sliding member and a shield on one of the prongs of the opposite member adapted to be moved in clamping position with reference to the tooth member.

7. In a hair waver composed of two principal parts hinged together in scissors-like formation, one of said parts having two prongs with projecting teeth and the other of said parts having two prongs with openings to fit over or telescope said teeth, a 20 toothed sliding member between said toothed prongs having a heating unit, means for moving said sliding member longitudinally in relation to the projecting teeth of the main member and a detachable shield adapted to 25 be connected to either one of the prongs of the telescoping member, said shield being made of heat insulating material and adapted to be brought into clamping relation with reference to the toothed member adjacent 30 thereto.

8. The combination with the two principal forked elements hinged together in scissors-like formation with extending handles, one of said parts having toothed projections and 40 the other of said parts having perforated prongs adapted when the parts are closed together to fit over the teeth in the other part, a toothed sliding element arranged between the toothed prongs of one part, pivoted 45 levers having link connections connected to the sliding member at one end and to the pivoted member at the other end in a lazy-tongs formation, said levers being pivoted together and to the forked portion and extending backwardly into proximity of the 50 handles for operating the main parts.

9. In a hair waver composed of two principal parts hinged together in a scissors-like formation, one of said parts having two prongs with depending teeth and the other part having a similar number of prongs with perforations to fit over said teeth, a sliding element between the toothed prongs of one member provided with an electrical heating 55 unit, means for manipulating said parts to open and close the same and means consisting of pivoted levers and springs for causing a longitudinal movement of said sliding element with relation to said toothed prongs.

60 10. In a hair waver composed of two

principal parts pivoted together in scissors-like formation with handles for opening and closing the parts with relation to each other, one of said parts having prongs with depending teeth and the other part having similar 70 prongs with openings to fit over said teeth and a detachable shield having means for securing the same to one or the other of said perforated prongs to form a clasp between that prong and its corresponding prong in 75 the other part.

11. A hair waver which consists essentially of two parts hinged together in scissors-like formation, each of the parts being forked with extending prongs, each of the prongs 80 in one of the parts having comb-like teeth and the prongs in the other part having slotted openings to fit over said teeth, a sliding element located between the toothed prongs of one member, handles on the pivoted portion for opening and closing the same and means in proximity to these handles for causing a sliding movement of the sliding member.

12. In a hair waver, two parts hinged together in scissors-like formation, each of said parts having a pair of projecting spaced-apart members, a series of teeth arranged on each of the members of one of the parts, said teeth when the said parts are 90 closed together straddling portions at least of the members of the other part, a sliding element located between the toothed members, and means for causing a sliding movement of said sliding member.

100 In testimony whereof, I have hereunto set my hand this 4th day of December, 1930.

CHARLES A. BUCHANAN.
